DESIGN FOR A COAL BURNING STOKER

John R. Whitehead, Chicago, Ill., assignor to
Fairbanks, Morse & Co., Chicago, Ill., a corpo-
ration of Illinois

Application August 10, 1934, Serial No. 52,891

Term of patent 3½ years

To whom it may concern:

Be it known that I, JOHN R. WHITEHEAD, a citizen of the United States, residing in the city of Chicago, in the county of Cook and State of Illinois, have invented a new, original, and ornamental Design for a Coal Burning Stoker, of which the following is a specification, reference being had to the accompanying drawing, forming part thereof.

The drawing illustrates, in perspective, a coal burning stoker embodying my new design.

I claim:

The ornamental design for a coal burning stoker, substantially as shown.

JOHN R. WHITEHEAD.
